METHOD AND MEANS FOR FORMING BLAST HOLES IN SULFUR STOCK PILES

Arnold F. Zemanek and Herbert E. Treichler,
Newgulf, Tex., assignors to Texas Gulf Sulphur
Company, Newgulf, Tex., a corporation of Texas

Application August 5, 1946, Serial No. 688,585

6 Claims. (Cl. 18—45)

1

The invention relates to a means and method of forming blast holes in sulphur stockpiles.

In the mining of sulphur, the crystalline sulphur deposits in the earth formations are melted usually with steam or hot water, and the sulphur raised to the surface in liquid form of approximately the consistency of water.

It is most often desirable to store the sulphur until it is to be sold and the practice is to deposit it in layer upon layer within a retaining wall until an enormous block or stockpile of sulphur is formed. These blocks usually approximate three hundred to five hundred feet in width and five hundred to twelve hundred feet in length, and may be fifty or sixty feet in height. When the sulphur is to be shipped, it is the usual practice to blast off portions of the block. The present practice is to drill blast holes in the solidified crystalline sulphur and position explosives in the hole so as to blast off portions of the pile.

The present invention contemplates the formation of the blast holes as the stockpile is formed so as to eliminate the cost and inconvenience of drilling the blast holes.

It is one of the objects of the invention to provide a nipple which is of a size of the desired blast hole and of a length which may be readily moved step by step as the stockpile is built so as to form a hole in the sulphur which results in a continuous blast hole from the top to the bottom of the sulphur pile when the pile is completed.

Another object of the invention is to provide a nipple for forming blast holes for sulphur stockpiles.

A still further object of the invention is to provide a means and method of forming blast holes in sulphur stockpiles and to provide a detonation chamber adjacent the base of the blast hole.

Other and further objects of the invention will be readily apparent when the following description is considered in connection with the accompanying drawing, wherein—

Fig. 1 is a perspective view of a sulphur stockpile which has been created in accordance with the present invention;

Fig. 2 shows one of the blast hole forming nipples in position with a box-like member about it to create a detonation chamber in the stockpile;

Fig. 3 shows one of the nipples chucked in the stockpile which has already been formed so as to create a continuation of the blast hole as the

2

nipple is moved step by step upwardly upon creation of the stockpile.

In Fig. 1 the block 2 represents a stockpile of sulphur and having a plurality of blast holes 3 arranged therein. These blast holes are shown as extending from the top to the bottom of the block of sulphur and each blast hole is arranged to receive a charge of explosive to be set off in blasting off a portion of the pile.

In Fig. 2 the surface 4 is the surface on which the stockpile 2 is to be built and the nipple is in the form of a cylindrical body portion 5 and a lower tapered portion 6. These two portions merge at 7 as a continuous nipple or pipe. In actual use, the body portion 5 will be about three and one-half inches in diameter, and the total length of the nipple will approximate four feet. The lower end may be closed with a partition 8, or it may be opened as desired.

The nipple will be inserted into the surface 4 a short distance so that it will stand erect and the liquid sulphur then deposited on the surface 4 in shallow layers an inch or two in thickness. The sulphur soon solidifies and then an additional layer will be deposited until the block of sulphur is built up to a thickness approximating the tapered length of the nipple. The nipple is made of aluminum and the sulphur does not bond therewith so that the nipple may be readily loosened and elevated to a position shown in Fig. 3, where the body of sulphur 10 has the hole 11 formed therein which is an increment of one of the blast holes 3 seen in Fig. 1. The tapered portion 6 facilitates to some extent the raising of the nipple, and it is desirable now to support the nipple in such raised position. The liquid sulphur congeals gradually and a small amount 12 of liquid sulphur in partially congealed form can be readily placed around the nipple 5 so as to chuck it in position and prevent its dropping down into the hole 11. The additional layers of sulphur are now deposited, and these operations repeated time after time until a pile fifty or sixty feet in height is formed. The increments 11 of the hole when added together provide the blast hole 3.

In some instances it may be desirable to form a detonation chamber about the base of the blast hole and Fig. 2 shows a box-like member 15 arranged around the nipple and having a lid or cover 16 thereon. This member 15 may be of combustible material such as paper, and a section of ordinary mailing tube say eight inches in diameter may be used. When the detonation occurs, the fiber material will be consumed.

While the nipples have been described as of aluminum, it is preferable that they may be made of a material having a higher coefficient of expansion than sulphur so that upon cooling it will shrink away from the sulphur. The material should not corrode when in contact with sulphur.

Broadly the invention contemplates a means and method of preforming blast holes in sulphur stockpiles as the stockpile is completed.

The invention claimed is:

1. A nipple for the forming of blast holes in a sulphur stockpile comprising a tubular section approximating the diameter of the blast charge, a tapered section joining one end thereof, said nipple to be positioned where a blast hole is to be provided in the stockpile so that as the molten sulphur is deposited therearound and whereupon the nipple may be progressively raised step by step as the sulphur of the stockpile solidifies whereby there is formed a continuous hole in the sulphur, and a closure wall at the lower end of said tapered section to exclude sulphur.

2. A method of progressively forming a plurality of blast holes in a sulphur stockpile which comprises positioning a plurality of relatively short hollow partially tapered nipples in the stockpile area one at each location where a blast hole is desired, progressively depositing layer after layer of sulphur in liquid form about the area and around the nipples until the body of sulphur thus created approaches the top of the tapered portion of the nipples, then raising the nipples in the solidified sulphur, chucking the nipples with congealing sulphur so as to thereafter exclude molten sulphur from the hole, depositing additional layers of sulphur to accumulate the stockpile, and continuing such operations until the stockpile is completed, and removing the nipple to leave the thus pre-formed blast holes in the pile.

3. A method of progressively forming a plurality of blast holes in a sulphur stockpile which comprises positioning a plurality of hollow nipples in the stockpile area one at each location where a blast hole is desired, arranging a box-like member about each nipple to form a detonation chamber, depositing layer upon layer of sulphur in liquid form about the area and around the nipples until the body of sulphur thus formed approaches the top of the tapered portion of the nipples, then raising the nipples and chucking them in raised position with congealing sulphur, depositing additional layers of sulphur, continuing such operations until the stockpile is completed, and removing the nipple to leave the blast holes in the pile.

4. A method of progressively forming a plurality of blast holes in a sulphur stockpile which comprises positioning a plurality of hollow nip-

ples in the stockpile area one at each location where a blast hole is desired, arranging a box-like member of combustible material about each nipple to form a detonation chamber, depositing layer upon layer of sulphur in liquid form about the area and around the nipples until the body of sulphur thus formed approaches the top of the nipples, then raising the nipples and chucking them in raised position with congealing sulphur,

5 10 15 20 25 30 35 40 45 50 55 60 65 70 75 80 85 90 95

depositing additional layers of sulphur, continuing such operation until the stockpile is completed, and removing the nipple to leave the blast holes in the pile.

5. A nipple for the forming of blast holes in a sulphur stockpile comprising a tubular section, a tapered section joining one end thereof, said nipple to be positioned where a blast hole is to be provided in the stockpile so that the nipple may be progressively raised step by step as the stockpile is formed to provide a continuous hole in the sulphur, said nipple approximating eighteen inches in length, and a closure for said tapered section.

6. A method of forming a sulphur stockpile to provide pre-formed blast holes therein which comprises, arranging a pre-formed pattern of blast hole nipples, depositing a layer of molten sulphur about such predetermined pattern of blast hole nipples, allowing the sulphur to solidify, periodically depositing and allowing solidification of the sulphur until the surface approaches the top of the nipples, raising the nipples in the solid sulphur, positioning the nipples in such raised position, and repeating such operations until the stockpile is formed so as to provide a plurality of continuous blast holes in the stockpile to receive the blast charges.
